CLAIM

The ornamental design for a coaster container, as shown and described.

DESCRIPTION

FIG. 1 is a front elevational view of a coaster container, showing our new design;

FIG. 2 is a side elevational view thereof;

FIG. 3 is a top plan view thereof;

FIG. 4 is a perspective view thereof; and,

FIG. 5 is a top plan view of another embodiment.

The portions of the peripheral member that are shown broken away indicate that the space between the two ends of the peripheral member may vary.
